J. THORP.
MACHINERY FOR SPINNING AND IN SPINNING COTTON YARNS.

Nov 11, 1830

John Thorp of Providence Rhode Island.

Letters Patent.

The subscriber referred to in these Letters Patent and making part of the same containing a description in the words of the said John Thorp himself of his improvement for spinning cotton yarn.

It is known that I John Thorp of Providence in the county of Providence & State of Rhode Island &c have invented a contrivance made and applied to use, new and useful improvement in machinery for spinning and in spinning cotton yarn, being improvements in my spinning cap spinner patented on thirtieth day of June A.D. 1829. by which is produced a new mode of obstructing the winding process of the yarn, causing it to fall back of the cap, and wind upon the bobbin. The spindle used is the common thruster spindle, two projecting lips are affixed to that part of it where the bobbin usually traverses. These lips are on opposite sides of the spindle, are parallel with it, and project about the depth of an inch. They extend up no farther than the face of the bobbin, when at its highest position, and these should be length enough to the spindle above them to allow the bobbin to be raised above them, to反转 on the spindle for the purpose of yielding the yarn for plying.

The common thruster fly is converted into what I call a cap, by affixing to the lower extremity of its arm, in a horizontal position a ring called the connecting ring, sufficiently large to allow the bobbin to traverse up and down through it. This ring guides the yarn to, and directs it on the bobbin. The yarn is not connected with the cap, but is left to revolve around its surface. The bobbin and the common thruster bobbin, with a channel or groove formed on one side of its periphery in which the above described lips of the spindle traverse, and by which the bobbin is made to turn

No. 45

with the spindle; or there may be a said spindle, a tube of the length of the bobbin, in which said one channel or groove, may be formed, having a large head or collar at the bottom on which the bobbin will loosely sit. This tube may be made of sheet iron and not entirely closed, and brayed to a head or collar of the same. In this case the opening in the side of the tube, will answer for one channel or groove, and the other channel or groove, and one of the lips on the spindle, may be suspended with the friction of the base of the bobbin on this head or collar will be sufficient to give motion to the bobbin, and the bobbin being allowed to turn on said tube, will at any time yield the yarn when it is needed, if should be drawn from it, as in plying the ends &c. Or instead of said lips on the spindle, grooves or channels may be made in it, and a collar such to give motion to the bobbin. This collar should be about the size of the base of the bobbin and made to slide loosely on the spindle. From the side of its perforation two lips project inward, and into the channels or grooves in the spindle causing the collar to turn with the spindle.

But the principal improvement consists in a stationary spiral lip or rim, that I call the cheek, the upper edge of the cheek is within the connecting ring, one end, or part of this cheek is fixed, and remains above this ring, while the other end remains below it.

The space between the inside of this ring and the outside of the cheek, should be large enough to allow the yarn to roll freely in it. The friction or tension requisite to wind the yarn upon the bobbin, is produced by the upper edge of the cheek, over which the yarn is drawn or compelled to pass at every turn of the spindle.

The cheek is a thin piece of metal, but flatwise forming a curve corresponding with a circle less in diameter than that of the ring.

It is fastened to above this is bolted or otherwise fastened to a fixed bar or rail that stretches along the spinning frame back of the spindle. By means of a staff or some bar in this place the cheek can be raised or lowered at pleasure, causing its uppermost lip above the bottom of the connecting ring, and per-

in an off angle in the yarn, consequently increasing or diminishing the friction or tension of the yarn, and winding it more or less tight on the bobbin, said check should extend half way round the bobbin though a greater or less proportion may answer the purpose.

Small polished notches or projections, on the upper edge of the check will produce an increased tension on the yarn. The yarn falls down on the outside of the connecting ring, or lower edge of the cap, then up between said ring and the check and over the upper edge of the check to the bobbin.

Among the several improvements above described there is but one in which I claim an exclusive property, and that is the check as afore described, by which the progress of reducing the yarn is obstructed, the yarn made to fall back of the cap and to wind on the bobbin.

Providence R. I. Nov 1st 1830.
